Wm. Ralph

United States Patent Office.

WILLIAM RALPH, OF UTICA, NEW YORK.

Letters Patent No. 65,828, dated June 18, 1867.

MILK-CANS.

The Schedule referred to in these Letters Patent and making part of the same.

TO ALL WHOM IT MAY CONCERN:

Be it known that I, WILLIAM RALPH, of the city of Utica, in the county of Oneida, and State of New York, have invented a new and useful improvement in Milk-Cans, by a combination and application thereto of a tipping socket and handle, attached to a single plate, whereby the same may be secured to the can.

This invention pertains particularly to that character of can used in conveying and delivering milk to "cheese factories," and has for its object a convenient means of handling the can, and rapidly discharging its contents, by raising the can, inverting it, and pouring from the top; and I do hereby declare that the following is a full, clear, and exact description of the construction and operation of the same, reference being had to the annexed drawings, making a part of this specification, the same letters in the respective figures referring to like parts.

Figure 1 is a representation of the usual carrying or delivery can as furnished with my improvement, the can being shown raised, ready to be discharged of its contents by tipping or turning on the axis made by the insertion into the sockets *a*—one each of which is attached on opposite sides of the can—of the tipping hooks *b*, fig. 1, by which the can may be raised, and swung to the desired position for emptying by a crane or other suitable device.

Figure 2 is an enlarged drawing of the plate *B*, to which is connected the socket *a*, and the hinged handle *C*, said hinged handle being shown raised and in position as used, when the can is being moved or lifted by hand, showing also the holes in the plate *B*, by which the said plate, socket, and handle are riveted or otherwise secured to the can.

Figure 3 is also an enlarged drawing of the said plate, socket, and handle, showing the hinged handle at rest, or in position, as when not in use, or when the can is used as at fig. 1.

What I claim as my invention, and desire to secure by Letters Patent, is—

1. The socket *a*, when applied substantially as described, for the purpose mentioned.
2. The combination of the plate *B*, socket *a*, and handle *C*, for the purpose set forth.

WM. RALPH.
